UNITED STATES PATENT OFFICE.

HERBERT C. WARREN, OF HARTFORD, CONNECTICUT.

GEAR-TOOTH-GENERATING MACHINE.

SPECIFICATION forming part of Letters Patent No. 605,983, dated June 21, 1898.

Application filed December 15, 1897. Serial No. 661,986. (No model.)

To all whom it may concern:

Be it known that I, HERBERT C. WARREN, a citizen of the United States, residing in Hartford, in the county of Hartford and State of Connecticut, have invented certain new and useful Improvements in Gear-Teeth-Shaping Machines, of which the following is a specification.

This invention relates to a machine or apparatus for shaping the side faces of gear-teeth, and is distinguishable from the class of machines known as "gear-cutting" machines and "gear-tooth-generating" machines in that the present machine is not intended to generate a tooth by cutting successive tooth-spaces in a blank, but is primarily intended to shape, true, dress, or finish the side faces of the teeth of a rough or an approximately true gear or toothed-gear blank.

An object of my present invention is to furnish a machine or apparatus of the class specified comprehending a gear-blank carrier and means, including a planing, dressing, or compressing tool, for planing, dressing, or compressing the side face of a blank-tooth transversely of its length, or from the crown to the base thereof, while rolling the gear-blank and planing-tool relatively to each other after the manner of two intermeshing gears.

A further object of the invention is to furnish a machine of the class specified comprehending an oscillatory gear-blank carrier; an oscillatory tool-carrier; a planing, dressing, or shaping tool supported on the tool-carrier in position to operate upon the side face of a tooth of the blank carried by the blank-carrier and having a serrated cutting-face of a length not less than the length of the tooth-face to be cut, and actuating mechanism embodying a connector between the two carriers and effective for simultaneously oscillating said carriers in a manner whereby the gear-blank and tool will have a rolling action one upon the other, and whereby the tool will at the same time have an advancing planing movement crosswise of the length of the tooth and from the top toward the bottom of the tooth-face and will remove successive full-length face portions of said tooth at successive points in such movements.

The principle developed in an apparatus including a planing, dressing, or shaping tool

operable for planing or dressing the side faces of the blank-tooth transversely of its length, or from the crown to the base, and at the same time rolling the gear-blank and planing or dressing tool one upon the other, involves a method which is, so far as I am aware, radically new in the art. Therefore it is distinctly to be understood that I do not limit myself to the specific means illustrated in the accompanying drawings for developing this principle, as modifications of such means may be practically employed within the purview of said invention.

In the drawings accompanying and forming part of this specification, Figure 1 is a side elevation of a portion of one simplified form of gear-tooth-shaping machine embodying my present invention. Fig. 2 is a vertical section taken on the dotted line *a a*, Fig. 1, and shows the parts at the right of said line. Fig. 3 is an enlarged sectional view of a portion of the toothed-gear blank and the planing-tool shown in Fig. 1, said section being taken on a line corresponding with the dotted line *b b*, Fig. 1, and shows a portion of the gear and planing-tool below said line. Fig. 4 is a diagrammatic view illustrating the operation of shaping or planing two opposite sides of two adjacent teeth by two planing-tools, the dotted lines tangent to successive portions of the tooth representing successive positions of the planing-face of said tool during the advancing movement thereof along the side face of the tooth from the top to the bottom thereof. Figs. 5 and 6 are end and side views, respectively, of one form of planing-tool having one inclined serrated cutting-face. Fig. 7 is an end view of a planing-tool having two oppositely-inclined serrated cutting-faces; and Fig. 8 is an end view of a tool of a general contour similar to that shown in Figs. 5 and 6, but having a smooth burnishing or compressing face.

Similar characters designate like parts in all the figures of the drawings.

As a preamble to the detailed description of the machine or apparatus illustrated in the accompanying drawings, it is desired to state that the terms "non-rotary," "shaping," or "planing" tool herein employed signify any suitable form of automatically-operated tool, other than a rotary cutter, capable of shaping

a gear-tooth face by cutting, dressing, scraping, filing off, or compressing portions of the metal of said face during a progressive rolling or advancing movement of said tool along and 5 from the top toward the bottom of said face, and, further, that the term "oscillatory movement" is herein applied to the tool-carrier and gear-blank carrier to avoid prolixity and signifies any "curvilinear" or "rotary reciprocatory" movement of said carriers.

The term "tool-carrier," in the broader sense thereof as employed in certain claims, signifies any suitable form of device embodying means for supporting the tool and for facilitating an oscillatory or rotary reciprocatory movement of said tool about an axis so disposed as to enable the tool to have a rolling action on the blank in the manner of the tooth of a gear rolling in the tooth-space of an in- 20 termeshing gear.

The apparatus illustrated in the accompanying drawings is shown, for the purpose of simplicity, as a special machine adapted for treating special size bevel-gears, and in so far 25 as the gear-blank carrier, tool-carrier, and connecting and actuating mechanism therefor are concerned they are similar in a general way to the apparatus described in my contemporaneously-pending application, Serial No. 642,612, filed June 28, 1897.

In the drawings I have shown two planing or dressing tools set side by side in position for planing or dressing opposite faces of adjacent teeth, one tool being positioned for operating upon and dressing one face of one tooth and the other tool for simultaneously operating upon and dressing the opposite face of the next adjacent tooth.

It is to be understood in the above connection, that while it is preferable to employ two planing or dressing tools so disposed as to operate upon opposite faces, respectively, of adjacent teeth simultaneously, I do not limit myself to the employment of any particular 45 number or disposition of such tools, as one or more tools may practically be employed and disposed in any suitable manner.

The framework, which may be of any suitable general construction, for supporting the 50 several fixed and movable parts of the machine is shown comprising a main body portion or bed B, having at one end thereof an upwardly-extended overhanging arm B', furnished at its upper end with a bearing 2, in 55 which is rotatably supported the gear-blank carrier C.

Extending upward from the opposite end of the bed B is a post B², having at the upper end a horizontal bearing 3, in which is journaled the rock shaft or stud 4 of the tool-carrier, which is designated in a general way by C'.

In the form thereof shown in the accompanying drawings the axis (indicated by the 65 dotted line x) of the blank-carrier C is oblique to and intersects the axis (indicated by the dotted line y) of the tool-carrier C', the point

of intersection of said axes being indicated by the dotted circle g, Fig. 1 of the drawings, said point of intersection being coincident 70 with the apex of the gear-blank cone illustrated in dotted lines in Fig. 1.)

The gear-blank carrier C and the tool-carrier C' of my present machine are shown similar in construction and organization to like 75 parts in the gear-tooth-generating machine described in Letters Patent of the United States No. 547,571, granted to me October 8, 1895, to which reference may be had.

The term "gear-blank" as herein employed 80 signifies any suitable form of blank having peripheral notches or tooth-spaces, each of which is of a depth equal to the depth of a finished tooth and of a width sufficient to permit the entrance and exit of the planing or 85 dressing tool T.

The tool-carrier C', in the preferred form thereof shown in the accompanying drawings, comprises three members, one of which is in the nature of a tool-slide carrier (designated in a general way by C²) supported for oscillatory movement about the axis y, and the other two members of which are shown as tool-slides 5 and 6, supported on the tool-slide carrier C² for adjustment in paths intersecting the path of oscillation of said carrier and in paths radial to a common center.

The planing or dressing tools, which are shown as two in number and each of which is designated by T, are supported side by 100 side with their cutting or dressing faces in oblique planes radial to the common center g, said tools being fixedly secured to the tool-slides 5 and 6.

The tool-slides 5 and 6 are preferably supported for adjustment in guideways 5' and 6' on the slide-carrier C² and are located one at each side the oscillatory path of movement of said carrier.

The gear-blank carrier C, which may be 110 similar in a general way to the gear-blank carrier described in the patent referred to, is shown in Fig. 1, comprising an arbor or spindle journaled for rotary reciprocatory movements, as before stated, in the bearing 2 at 115 the upper end of the overhanging arm B'.

The gear-blank, which is designated by G, may be secured to the blank-carrier in any suitable manner.

As a simple and convenient means for 120 imparting oscillatory or rotary reciprocatory movements to the tool-carrier and blank-carrier simultaneously and also for maintaining a predetermined ratio of velocity between said carriers, I have provided an actuating- 125 connector between and directly connecting the two carriers, and adapted, when one carrier is oscillated, for effecting an oscillatory movement of the other carrier simultaneously, and I have provided, in connection with 130 one of said carriers, a carrier-oscillating device which may in practice embody means whereby the range of oscillatory movement of said carrier may be arbitrarily changed.

The actuating-connector between the two carriers comprises, in the preferred form thereof shown in the accompanying drawings 5 two oscillatory members (designated by *c* and *c'*) secured to the two carriers *C* and *C'*, respectively, and so connected at their adjacent ends that an oscillatory movement of one carrier and the member secured thereto will impart an oscillatory movement in the same direction to the other member and its carrier. These two oscillatory members *c* and *c'* are shown in the nature of intermeshing bevel-gear segments, one of which, as *c*, is removably secured to the gear-blank carrier 10 *C*, and the other of which, as *c'*, is removably secured to the tool-carrier *C'*, the apex of the tooth-face angles of the bevel-gear segments *c* and *c'* being coincident with the common center *g* or the point of intersection of the axial lines *x* and *y* of the two carriers *C* and *C'*.

As a convenient means for actuating one of the carriers to effect an oscillatory movement of both carriers I have provided a carrier-oscillating device, which is designated in 25 a general way by *H* and which in the accompanying drawings is shown in operative connection with the tool-carrier *C'*. The carrier-oscillating device *H* is shown comprising a pitman 9, pivotally secured at its upper end 30 to the outer end of a crank-arm 10, fixed to the rock-shaft 4 of the tool-carrier and pivotally secured at its lower end to a crank-pin 12 on a rotating member 13, fixed to the shaft 14, journaled in a bearing 15 on the base *B* 35 of the machine, and which shaft 14 is provided at the opposite end thereof with a band-wheel 16, which may be driven by a belt and from any suitable source of power. (Not shown.)

To form a theoretically-correct tooth-face 40 by a tool having its effective working strokes at successively-changing angles tangent to the tooth-face in a direction transverse to the length of the tooth and to facilitate the removal or shaping of successive full-length 45 portions of said tooth-face during the movements of said tool from the crown to the base of said tooth, it is necessary to employ a planing or dressing tool of peculiar construction.

The preferred form of planing or dressing 50 tool employed in connection with the other parts of the apparatus illustrated in Fig. 1 of the drawings comprises an elongated bar or plate 17, of a maximum thickness less than the width a tooth-space of the gear-blank and 55 of a length preferably not less than the length of the tooth-face to be shaped, said bar having an inclined serrated cutting, dressing, or compressing face 18, the serrations of which extend longitudinally thereof from end to 60 end, the narrowest portion being at the forward end of the tool, as will be understood by reference to Figs. 1, 5, and 6 of the drawings.

In Fig. 7 the tool *T* is shown having a truncated V-shaped cutting end the opposite faces 65 of which are serrated in the same manner as the one face of the tool illustrated in Figs. 5 and 6.

In the operation of shaping a tooth-face by my improved apparatus illustrated in the accompanying drawings the tool *T* has a motion 70 with relation to the tooth-face it is operating upon similar to the motion of a tooth of a gear rolling upon the tooth of an intermeshing gear, the cutting or dressing face 18 of the tool during the rotary reciprocatory movements of the gear-blank *G* and planing-tool *T* assuming the successively different angles indicated by the dotted lines *h*, *i*, *j*, *k*, *l*, *m*, and *n* in the diagram Fig. 4, said tool simultaneously advancing along the side face of 80 the gear-tooth from the crown to the base thereof and cutting, dressing, or shaping successive full-length portions of said face, the cutting-faces 19 of the serrations of the planing or dressing tool being disposed substantially at right angles to the line of movement of said tool.

In practice the machine will be provided with suitable mechanism for indexing the blank, which mechanism may be similar to 90 that shown and described in the patent referred to.

Having described my invention, I claim—

1. A gear-tooth-shaping machine comprehending a carrier for the gear-blank; a non- 95 rotary shaping-tool mounted, with respect to the blank, to have a working stroke in a curvilinear path transverse to the longitudinal plane of the tooth being operated upon; and means for actuating the tool.

2. An apparatus of the class specified comprehending an oscillatory gear-blank carrier; an oscillatory tool-carrier; a non-rotary shaping-tool mounted on the tool-carrier in position to operate upon toothed portions of the 105 blank carried by said blank-carrier; and actuating means for imparting to the tool a curvilinear working stroke along the side face of the tooth from the crown to the base, and in a plane transversely of the length of, said 110 tooth, and for concurrently oscillating the gear-blank carrier on its axis.

3. The combination, in a machine of the class specified, of an oscillatory blank-carrier; an oscillatory tool-carrier; a planing-tool 115 mounted on the tool-carrier in position for operating upon the side face of the tooth of the blank carried by the blank-carrier, and having a serrated cutting-face; and actuating mechanism embodying a connector between the two carriers, and effective for simultaneously oscillating said carriers in a manner whereby the gear-blank and tool will have a rolling action, one upon the other, and whereby the tool simultaneously will 125 have an advancing working stroke crosswise of the length of the tooth, and from the top toward the bottom of the tooth-face, whereby to remove successive face portions of said tooth at successive points in such movement. 130

4. An apparatus of the class specified comprehending a carrier for the gear-blank; a tool-carrier; a non-rotary shaping or dressing tool mounted on the tool-carrier in posi-

tion for operating on the blank; and means, embodying a connector between the two carriers, for imparting to the tool a tooth-shaping stroke in a path transverse to the longitudinal plane of the tooth operated upon, and from the crown toward the base of said tooth, and for simultaneously imparting to the gear-blank a rocking motion relatively to the tool.

5. An apparatus of the class specified comprehending a carrier for the gear-blank; a tool-carrier; a planing-tool mounted on the tool-carrier in position to operate upon the side face of a tooth of the gear-blank, and having a serrated cutting or dressing face; and actuating means for imparting to the tool a working stroke in a curvilinear path transverse to the longitudinal plane of said tooth, and from the crown to the base thereof.

10. An apparatus of the class specified comprehending a gear-blank carrier; a tool-carrier; a planing-tool mounted on the tool-carrier in position to operate upon the side face of a tooth of the gear-blank carried by the carrier, and having a serrated cutting-face 15 of a length not less than the length of the

tooth-face being operated upon; and actuating means operatively connecting the two carriers and effective for imparting to the tool a curvilinear working stroke transversely of the length of the tooth-face, without movement of said tool longitudinally of the tooth, and from the crown to the base thereof, and for concurrently oscillating the gear-blank carrier whereby to effect a rolling action between the blank and tool.

15. A gear-tooth-shaping machine embodying, in addition to a carrier for the gear-blank, a non-rotary shaping-tool mounted to have a curvilinear working stroke, with respect to the tooth to be shaped, in the direction of curvature of said tooth and transverse to the longitudinal plane thereof, and means embodying an actuating-connector between the two carriers for effecting a motion of the gear-blank concurrently with, and corresponding 40 to, the curvilinear motion of the tool.
